UNITED STATES PATENT OFFICE.

ERNEST FURST AND SAMUEL TAVE, OF NEW YORK, N. Y.

LAMP-SHADE HOLDER.

Application filed February 21, 1925. Serial No. 10,809.

This invention relates to a lamp shade holder. The object of the invention is the production of a lamp shade holder which can be easily clamped to or detached from its supporting element. The second object of the invention is the production of a holder with clamping means, by which it can be detachably connected to a supporting element, without the use of screws, bolts, keys or other means that require adjustment.

The organization of the invention comprises a holder with a cam that can lock with or be clamped to a supporting element of a lamp.

In the accompanying drawings Fig. 1 represents an elevation of the lamp shade holder with a table lamp; Fig. 2 shows an enlarged fragmentary portion of Fig. 1 with its elements in a slightly changed position; Fig. 2^a shows a vertical section of Fig. 2 on the line 2^a, 2^a of Fig. 3, Fig. 3 indicates a bottom plan view of a portion of Fig. 2; Fig. 4 shows a side view of a bed lamp with the shade holder incorporated therewith; Fig. 5 represents a right hand side view of Fig. 4; Fig. 6 indicates an enlarged fragmentary portion of Fig. 4; Fig. 7 shows a top plan view of a modification of the shade holder with its shade; Fig. 8 is an enlarged fragmentary portion of Fig. 7 and Fig. 9 shows a section of Fig. 8 on the line 9, 9.

Referring to Figs. 1, 2 and 3, a lamp stand 15 is indicated with the neck 16. A lamp socket 17 is shown with its flared base 18, its clamping sleeve 20 and its bulb 24. The sleeve 20 is secured to the neck 16 by means of the clamping screw 25 having the shank 26.

The lamp shade holder comprises the clamping bar 30 with a central portion 31, having the circular opening 32 with the extension 33. From the lower face of the central portion 31 extends the annular cam with the central high portion 35 and its tapered end portions 36. A frame in this instance comprises the horizontal circumferential member 38, which is fastened to the ends of the bar 30. Bows 39 extend from the member 38 and support the shade or curtain 40.

The clamping bar 30 is placed in position with its opening 31 encircling the clamping sleeve 20, and the cam with its cam surfaces is brought to bear against the shank 26 of the screw 25, whereby the clamping bar 30 is tightly and adjustably clamped in place.

The extension opening 33 enables the clamping bar 30 to clear the head of the screw 25, when the former is placed in position on the clamping sleeve 20.

Referring to Figs. 4, 5 and 6 the clamping bar is indicated in this instance by the numeral 42 and is shown with a bed lamp. The bed lamp is indicated with the frame having the side portions comprising the vertical members 45, that have formed therewith the hooks 46. The vertical members are continued to form the horizontal members 47 and from the latter extend the curved members 48. The upper ends of the latter are connected to the vertical members 45. Horizontal members 50 connect the side portions of the frame.

The ends of the clamping bar 42 are fastened to the members 45 and 48 of one of the side portions of the frame of the lamp. The clamping bar 42, see Fig. 6 is again shown with a central portion 56, similar to 31 and the opening 57 similar to 32 and the extended opening 58 similar to 33. The central portion 56 has extending therefrom the cam with the high portion 60 and the tapered end portions 61, respectively similar to 35 and 36. The bar is however modified by having formed in its central portion 56 an opening 62. The lamp socket is again shown at 17 with its flared base 18, its clamping sleeve 20 and its bulb 24 with its coil 65 for electric current. The opening 62 serves as a clearance space for the coil 65 when the lamp socket is clamped in place. A shade or curtain 66 is provided for the frame of the lamp. The lamp socket is again secured in place as already described by engaging the shank of the screw 25 with the cam of the clamping bar 42. The hooks 46 are engaged with the head 68 of a bed or any other support.

Referring to Figs. 7, 8 and 9 the invention is modified by using a pair of clamping bars 100 connected to each other instead of one. A pair of clamping bars 70 and 71 are shown at right angles to each other. Central portions 72 and 73 similar to 31 are provided for the bars, with their openings 74 similar to 32. The bars 70 and 71 are placed one over the other and clamped to each other by means of the sleeve 75. The said sleeve 75 on its lower edge has formed therewith a cam with the high portion 76 similar to 35 and the tapered end portions 77 similar to 36.

A frame for a lamp shade is shown with the inner cylindrical ring 80 and the outer cylindrical ring 81. Ribs 82 connect said rings. The clamping bars 70 and 71 have their ends connected to the ring 80. The lamp socket is indicated with the bulb 85, its sleeve 86, and clamping screw 87. The shank of the screw 87 is clamped to the cam as already described. A shade or curtain 90 is provided for the frame of the lamp.

Various modifications may be made in the invention and the present exemplification is to be taken as illustrative and not limitative thereof.

Having described our invention what we desire to secure by Letters Patent and claim is:

1. The combination of a frame, a clamping bar with its ends fastened to the frame, said bar having a central portion with an opening, and said central portion having a clearance opening extending therethrough, a cam extending from said bar, and a lamp socket having a sleeve located in the opening of said central portion, said bar adapted to be locked in place by said cam.

2. In combination, a frame for a lamp, a clamping bar with its ends fastened to the frame, said bar having an opening, an annular cam extending from said bar adjacent to its opening, and a lamp socket with a portion thereof located in the opening of said bar, said cam coacting with said lamp socket to detachably lock the bar in place.

3. In combination in a lamp shade holder,

of a frame for the lamp thereof, a clamping bar with its ends fastened to the frame, said bar having an opening, an annular cam with tapered ends extending from said bar adjacent to its opening, a lamp socket with a sleeve, and a screw in engagement with said sleeve, said sleeve located in the opening of the bar, said screw coacting with said cam to clamp the bar in place.

4. In combination, a frame for a lamp, a pair of clamping bars one over the other with their ends fastened to the frame, means to clamp the bars to each other, said bars having an opening extending therethrough, a cam extending from one of said bars and a lamp socket with a portion thereof located in the opening through the bars and coacting with said cam to detachably lock the bars in place.

5. In combination, a frame for a lamp, a pair of clamping bars one over the other, with their ends fastened to the frame, said bars each having an opening axial with each other, a sleeve in said opening clamping the bars to each other, a cam formed with one end of said sleeve and a lamp socket with a portion thereof located in said opening said bars adapted to be locked in place by said cam.

Signed at the borough of Manhattan, city of New York, in the county of New York and State of New York this 16th day of January A. D. 1925.

ERNEST FURST.
SAMUEL TAVE.
